G. MARSDEN

VENDING MACHINE

Filed June 4, 1925

FIG. 1.

INVENTOR

GEORGE MARSDEN,

By: Otto D. Kueger,
his Atty.

Patented Oct. 23, 1928.

1,689,039

UNITED STATES PATENT OFFICE.

GEORGE MARSDEN, OF LOS ANGELES, CALIFORNIA.

VENDING MACHINE.

Application filed June 4, 1925. Serial No 34,895.

This invention relates to devices for delivering articles in certain quantities by coin-controlled apparatus.

One of the objects of this invention is to provide a base-member, above which articles to be vended are disposed, having a recessed guideway into which certain of the articles may drop to be separated from the other articles upon operation of coin-controlled apparatus.

Another object is to provide a drum with its turning axis vertically disposed and with means on its periphery by which articles may be stored one on top of the other in several sections around the drum preparatory to being vended from the turning drum.

Another object is to provide a base for such a turning drum with a curved recess partly in the path of the stored articles in the drum and curved outwardly from such a path to guide certain of the stored articles from the storing position so that they may be taken by an operator.

Other objects will appear from the following description and appended claims as well as from the accompanying drawing, in which—

Fig. 1 is a horizontal section on line 1—1 of Fig. 2, showing articles stored in the rotating drum, and showing some of the articles from the lower layers of the several sections deflected from their rotating path to a discharging position in the curved recess of the base-member.

Fig. 2 is a fragmentary vertical section on line 2—2 of Fig. 1, illustrating a coin in position so that the rotating drum may be actuated to advance the stored articles over the recess in the base-member and thereby to a discharging position, the coin-holder being in this view illustrated in a position in line with the section line 2—2 though the same coin-holder is shown in inoperative position as illustrated in Fig. 1.

The drum 3 is provided with several vertically disposed partitions 4, forming storing sections 5 for the articles 6 to be dispensed or vended by an apparatus. This drum is preferably rotatable around a centrally disposed shaft 7.

The articles to be vended are not directly supported by the drum but are loosely disposed in the sections 5 one on top of another article, the several piles of articles resting

shiftably on a base-member 8. The lowermost layer of the articles, or the lowermost article of each of the piles in the several sections is directly resting on the base, and is shifted over the surface of the base-member when the rotating drum is actuated. The stored articles are under these conditions moved over the surface of the base-member in a certain circular path.

A certain portion of the surface of the base-member, covered by the stored articles, within such circular path is provided with a recessed path of a size that the whole pile of any section may drop to a limited extent into this recessed path at a certain point or position when the storing drum is so rotated or moved.

The general top surface of the base-member is indicated by the arrow 9, while the lower surface of the recessed path is indicated by the arrow 10 in Fig. 2. The beginning of the recessed path is indicated at 11 in Fig. 1, so that the pile reaching the point or position indicated by the numeral 12 tends to drop to a lower position or level than occupied previous to reaching the beginning 11 of the path.

The recessed path deflects from the circular path in an evenly curved manner towards the outside as indicated at 13 in Fig. 1.

Upon reaching the position indicated at 14, any article dropped into the curved path or guideway is separated from the pile resting upon such lowermost article while the remaining articles in the same pile are caused to follow the general circular path within the housing 15.

The outermost edges 16 of the drum tend to push the separated article into the discharged position indicated at 17. The discharged articles may then easily be taken from the apparatus by the operator.

A coin 18 is shown in operative position in an actuator 19. The actuator is pivotally and swingably mounted on the lower end of the shaft 7 as indicated at 20 in Fig. 2, and may be moved to bring the coin into operative engagement with one of the partitions 4 so that the drum can be turned or rotated around its axis by such movement of the actuating member 19. From the inoperative position indicated at 21 in Fig. 1, the coin may be moved to the point indicated in dotted lines at 22, being the distance equal to

the width of one of the sections of the drum, and coming to the point indicated at 22 the coin drops out of engaging position.

The base-member 8 is for this reason and 5 purpose provided with a coin-supporting flange 23, as illustrated in Figs. 1 and 2, extending from a point near the inoperative position of the actuator to a point short of the point to which the actuator with the coin may 10 be moved in operative position.

As illustrated in Fig. 2, the coin rests on the flange 23, which is slightly inclined in its upper surface so that the coin is caused to roll against the edge 24 of the base-member 8. 15 In this position within the slot of the actuator the coin remains while shifted from the inoperative position to the termination of the shifting or moving of the actuator, the coin sliding through the shifting movement 20 of the actuator over the surface of the flange 23 until the coin passes beyond the termination 25 of the flange. On passing the edge 25 of the flange 23, the coin simply drops from the flange into the hollow of the base 8.

25 While the coin is in operative position it extends upwardly far enough to engage the drum for the turning operation.

I claim—

1. In a vending machine, a base-member, a 30 storing drum disposed rotatably above the base-member having vertically disposed sec-

tions in which articles may be held and moved in a circular path one on top of another preparatory to being vended, the base-member having a recessed path and guideway below 35 the stored articles and of a form so that the whole pile of stored articles in any of the sections of the drum may drop to the extent of the depth of the recessed path upon reaching a position above the path, the guideway being 40 curved outwardly from such circular path including a discharging opening in the base so that articles may be caused to discharge from the stored piles upon rotation of the drum, and means for rotating the drum. 45

2. In a vending machine, a storing drum disposed to rotate around a vertical axis having means on its periphery for holding articles to be vended to rotate around such vertical axis in a circular path, a base-member having means to support said drum for rotating movements and having a discharging means in its top surface below said circular path and curving outwardly from such circular path in a practically horizontal plane 55 by which stored articles may be separated from the drum preparatory to being discharged, and means for discharging these separate articles by a rotating of the drum.

In testimony that I claim the foregoing as 60 my invention I have signed my name.

GEORGE MARDEN.
